CHARLES A. ROWLEY, OF BLOOMFIELD, NEW JERSEY, ASSIGNOR TO THE RAJAH COMPANY, OF BLOOMFIELD, NEW JERSEY, A CORPORATION OF NEW YORK

CONNECTER

Application filed January 5, 1931. Serial No. 506,569.

This invention relates to a connector for electrical circuit elements and particularly to a connector adapted to be locked in place so as to prevent its separation except by a manipulation which is substantially impossible of accidental accomplishment.

A great many and varied types of connectors have been proposed and used prior to my invention for making and holding a satisfactory electrical contact and mechanical connection between separable elements of an electrical circuit. For many uses the problem is not a particularly difficult one and many of the types of connections heretofore known have proved inexpensive to manufacture and satisfactory in operation. For certain purposes, however, the problem has not been solved. One of the most exacting of such uses is the connection of ignition wires to spark plugs and distributors, etc. of aviation engines. The connection is subjected to severe vibration and to repeated connection and disconnection which try to the limit the ability of the connection to hold under all circumstances. In aviation engines, in particular, the circuit must be maintained, since a break may often mean the wrecking of an expensive ship and frequently the loss of life as well. In view of this situation, repeated efforts have been made to provide some locking means which would be secure against disengagement by any accidental means and yet which could be quickly connected or disconnected during repair and/or inspection operations. Of these none has been so satisfactory as to entirely meet the scrupulous demands of aviation.

In the co-pending application of George H. E. Berthold and myself, Serial Number 466,438, filed July 8, 1930, is disclosed one type of locking connection which has proved more secure against accidental displacement than any other heretofore known. This type of terminal, however, fails to entirely meet the requirements of every case since it is necessarily a radial connection and occupies a considerable space, whereas in the design of many motors and particularly of radial motors, a more compact and more flexible

connection is desired since the space about the spark plug head is extremely limited.

Accordingly, it is an object of the present invention to provide a connection which will be absolutely secure against accidental disconnection, which will be compact and occupy a minimum of space and which will be flexible, permitting the wire or other circuit element to approach the spark plug (or other element) at almost any desired angle.

In the accompanying drawing in which I have shown a preferred embodiment of my invention—

Fig. 1 shows in perspective the connection made but not yet locked;

Fig. 2 is a view at right angles to Fig. 1, showing the connection after it is locked;

Fig. 3 is a view partially in longitudinal section taken on line 3—3 of Fig. 1, showing the method of making or breaking the connection;

Fig. 4 is a section on line 4—4 of Fig. 3;

Fig. 5 is a similar section showing the connection after it is locked; and

Fig. 6 is a view in perspective showing the several parts ready for assembling.

I have shown in the drawing the upper portion of a spark plug 10 having a ball terminal 11. The contact element of the connection consists of a common type of spring fork 12 shown best in Fig. 6. This fork has prongs 13, each of which is formed with a spherical depression 14 adapted to embrace the spherical face of the ball terminal 11. The ends of these prongs 13 are formed as shown at 15 with a flared lip adapted to act as a cam against the spherical face of the ball terminal 11 to spread the spring fork 12 when the fork is pushed over the ball terminal. The spring contact fork 12 is connected to the insulated conductor 16 in the usual way and in the preferred embodiment is also connected to an insulating ferrule 17 adapted to take the push and pull required for making and separating the contact and thus to relieve the strain from the conductor.

The contact as thus described is not essentially different from connectors which have been known and used for a number of years for connecting spark plug wires and avia-

tion engines. According to my invention, however, the contact once made is mechanically secured so that it cannot be separated without a special manipulation incapable of accidental occurrence. In order to effect this result a metal sleeve 20 is secured over the spring contact fork 12 so that it substantially fits the outside of the spring fork 12 when it is closed. This fit is sufficiently close so that when the sleeve embraces the fork 12 it will not tolerate the separation of the prongs 13 sufficiently to permit the ball terminal to leave the spherical depressions 14.

The sleeve 20 in the present embodiment of the invention is secured in position over the spring contact fork 12 by means of a locking spring 21. Prongs 22 on opposite sides of locking spring 21 fit into corresponding holes 23 near the base of the prongs 13 and extend therethrough a distance sufficient to permit their engagement in the annular groove 24 near the top of the sleeve 20. The end 25 of the spring 21 is also formed so that it extends beyond the side of the prong 13 and forms a latch engaging in the longitudinal groove 26 of the sleeve 20, as shown most clearly in Figs. 4 and 5. The several parts as shown in Fig. 6, are thus assembled by inserting the spring 21 between the prongs 13 with its prongs 22 extending through the holes 23. The sleeve 20 is then pushed over the end of the contact fork 12 and the spring 21 is contracted sufficiently to permit the prongs 22 to enter the sleeve 20 and engage in the groove 24.

In using the connection of my invention the sleeve 20 is turned as shown in Figures 1, 3 and 4 so that its opening 30 is aligned with one of the prongs 13. In this position the latch 25 will be engaged as shown in Fig. 4 in one of the four equally spaced longitudinal grooves 26. With the sleeve in this position the connector is pushed over the end of the ball terminal and as shown in Fig. 3 the prong 13 will be permitted to spring outwardly into the opening 30, thus allowing the terminal to enter between the prongs 13 and be received in the spherical depressions 14. Once the terminal has reached the spherical depressions 14 the prong 13 springs back to its original position and the sleeve 20 may be turned 90° to the position indicated in Figures 2 and 5. In this position uncut portions of the sleeve are behind the prongs 13 and serve to limit their outward movement so as to prevent their springing apart sufficiently to permit the ball terminal to leave the spherical depressions 14. In this position the connection is absolutely secure and cannot be separated except by such force as to destroy the connector itself. Nevertheless, the connection is entirely flexible, permitting the conductor to be bent down at right angles to the plug in any di-

rection or to be placed at any intermediate angle. The sleeve 20 is held in this locking position by the latch 25 which is engaged in a slot 26 as shown in Fig. 5.

To separate the connection, it is only necessary to turn the sleeve 20 once more through 90° and then to pull the connector from the ball terminal. In this position one of the prongs 13 being aligned with the opening 30 is free to flex outwardly and thus the prongs may be separated sufficiently to allow the withdrawal of the male terminal without substantial difficulty.

Although I have shown in the drawing and described above one embodiment of my invention, it will be understood that many changes and modifications thereof may be made without departing from the scope of my invention as claimed herein. Thus, instead of cutting away a portion of the sleeve, its interior may be shaped so as to be sufficiently wider on one diameter than on another so that the sleeve in one position will prevent the separation of the prongs 13 and in another position will permit sufficient separation to allow the male terminal to be introduced or withdrawn. Such arrangements are, however, less advantageous than that shown in the drawing. In particular, the provision of an opening 30 allows greater flexibility between the male and female terminals permitting them to be swung to an angle of 90° or less with the axis of the male terminal, which would not be possible if the openings were not provided.

Furthermore, when the male and female terminals are at an angle to each other, the neck of the male terminal engaging in the opening 30 serves as an additional lock to prevent any possibility of the sleeve being turned so as to permit accidental separation.

Other forms of female contacts may be used instead of the prongs 13 as illustrated. It is desirable, however, to have the contact between the sleeve and the back of the female terminal such that a force against the female contacts will not tend to move the locking sleeve to its disengaged position, otherwise the locking sleeve itself should be positively latched against accidental movement.

I am aware that prior to my invention it has been suggested to make connectors with female jaws which were to be closed over the male terminal by a longitudinal movable member acting upon the jaws by a cam action, e. g., against angular faces. As intimated above, such movable members do not constitute a satisfactory locking sleeve since the cam action is reversible and under an accidental stress may serve to release the jaws of the female terminal. Nor is this defect cured by the use of a sleeve moved longitudinally over the cam faces of the female jaws by means of a screw thread. The threads tend to hold the sleeve against direct

reversing of the cam action but, as is well known, screws are peculiarly subject to movement under vibration so that the female jaws may be entirely released merely by the vibration of the motor in operation.

5 The present invention is in contrast to these prior suggestions in that it contemplates limiting the contact jaws rigidly to prevent withdrawal from the male terminal, and 10 holding the limiting means in its locking position positively, as distinguished from any mere frictional engagement, e. g., as in the case of a screw thread.

Whatever form of female contacts are used, 15 it is to be understood that they should have longitudinally concave faces so as to require separation on withdrawal from the male terminal. By "concave" I do not intend to suggest a limitation to a smooth or continuous 20 curve since obviously the concavity could be angular without seriously impairing its function, or can be merely a hole which would accommodate the convexity of the male terminal.

25 Again, instead of using the locking spring 21 other means may be used for securing the sleeve rotatably to the female terminal and/or for holding the sleeve in its locking position. Thus, for example, an integral 30 prong could be pressed out from the female terminal into the groove 24 so as to hold the sleeve against removal and the edges of the prongs 13 could serve with a shallow longitudinal groove in the sleeve to latch the sleeve 35 in its limiting position. These and many other changes may be made without departing from the scope of the invention claimed herein.

What is claimed as new is:

40 1. A connector comprising a male terminal longitudinally convex in the direction of engagement, and a female terminal having separable prongs concave to embrace said convex part and engage therewith, a sleeve 45 rotatably mounted over said prongs having one side cut away to form an opening sufficiently large to permit one of said prongs to be moved outwardly into the opening when aligned therewith and having rigid 50 portions adapted to be simultaneously positioned behind said prongs and to limit their separation.

55 2. A connector as defined in claim 1 in which the male terminal is a ball terminal and the opening in the limiting sleeve is adapted to receive the neck of the male terminal so as to permit unobstructed angular movement between the male and female terminals when locked.

60 3. A detachable connector comprising opposite resilient prongs, each having a depression near its free end, a rigid sleeve rotatably secured over said prongs and having an opening in one side sufficient to permit one prong to be bent out into said open-

ing when aligned therewith, and means for holding the sleeve in a position in which the opening is between the prongs and rigid limiting portions of the sleeve are behind the prongs.

70 4. A connector as defined in claim 3, in which means for holding the sleeve in one position comprises a latch spring mounted between said prongs having a portion adapted to engage longitudinal grooves on the 75 inside of the sleeve and having projections extending through said prongs and engaging an annular groove in said sleeve so as to hold it rotatably over said prongs.

Signed at Bloomfield, N. J., this 11th day 80 of December, 1930.

CHARLES A. ROWLEY.
